SHOE AND METHOD OF MAKING SHOES

Aram Dagdigian, Reading, Mass., assignor to
Shoe Lace Company, Boston, Mass., a corpora-
tion of Maine

Application April 13, 1938, Serial No. 201,746

7 Claims. (Cl. 12—142)

This invention relates to improvements in shoes and methods of making shoes, and to improvements in insoles for shoes.

More especially it provides improvements for attaining a more efficient and satisfactory joinder of insole, outsole and the intervening lasted-over portion of the upper, in cement process shoes generally, and in McKay type shoes of openwork styles.

10 In the manufacture of cement process shoes capable of competing in price with the low-cost foreign importations, considerations of economy of manufacture frequently make it necessary to employ insoles made of inexpensive paper stock or of composition materials. In such cases the cement joinders, to the insole, of lasted over portions of the upper, and of the outsole, are apt to be insecure because of the tendency of the cement-carrying surface portion of the insole to peel from the main body of insole. Also, and regardless of the quality of insole, it has been practically impossible to attain any kind of a cement joinder of outsole to insole, at the region of the usual shank stiffener, except indirectly by adhesion of the outsole to the lasted-over portions of upper, which in turn are cemented to the insole.

Another problem, which has been present in McKay type shoes as well as in cement process shoes, is an incident of the trend to openwork styles of shoe uppers. In openwork designs, only discontinuous portions of upper are available for being lasted over the insole; and sometimes the width of these is merely that of straps. When the outsole is applied, the discontinuity of upper results in the formation of conspicuous openings extending inward between insole and outsole. These openings not only disfigure the shoe, they also are regions where no securing has been effected, or only an ineffective securing, of insole to outsole. If pressure is employed to force the outsole against the insole at these regions, objectionable irregularities result at the tread of the finished shoe, or in the insole interiorly of the shoe, or at both of these places.

It is an object of the invention to provide a combined attaching and filling means at the juncture of insole, upper and outsole, whereby a more effective securing of these elements together may be accomplished in cement process shoes—especially along the shank region and, in openwork styles, between discontinuous portions of lasted upper.

Another object is to improve the structure and appearance of shoes of the McKay type, particu-

larly openwork styles of McKay shoes, by utilizing a compressible element which becomes compressed where portions of upper are lasted over upon it, and which extends with full-bodied thickness between such portions of upper, for filling spaces which might otherwise be left vacant between insole and outsole.

A further feature resides in combining my improved attaching and filling strip with an edge binding for the insole, at locations of exposure 10 of insole edges in openwork shoes.

It is, moreover, an important feature that the invention may be embodied in shoes economically and expeditiously, its embodiment in openwork cement process shoes being a distinct aid in the 15 operation of binding the insole edges.

These objects and results may be attained, in a preferred form of the invention, by providing a compressible filler strip, preferably of material which is readily permeable by cement, and stitching that strip to the margin of the insole, on that side of the insole which will be toward the outsole in the finished shoe. This compressible strip will be one having substantial body. The stitching will extend along its outer edge, with the principal width of body of strip adapted to lie between the upper and the insole. Then, in an openwork shoe, the portions of upper which are present compress the body of the strip, leaving bulging portions of the strip at places where the upper 20 has been cut away, thickly tending to fill the spaces between the portions of upper.

In cement process shoes these bulged portions of strip are available for being secured by cement to the outsole as the latter is applied over the 35 lasted upper, thus providing means for securing of outsole to insole at regions where there is no portion of upper, as well as at places where portions of the upper are present. And the securing may thus be effected without such a 40 magnitude of pressure as would form waves on the tread or on the insole.

Also it is an important feature that the attachment of the strip is by stitches through the whole body of the insole, rather than merely to 45 its surface, thus eliminating the danger that surface layers, carrying the fastening, will peel away.

In the case of openwork cement process shoes, the said strip may be stitched to the insole simultaneously with the applying of the usual binding for the insole edges, that binding and the strip, by which the spaces are filled and the outsole made secure, being fastened by the same stitches.

The accompanying drawing illustrates the in- 55

vention by showing one of its possible embodiments, to which however the patent is not limited.

It is intended that the patent shall cover, by suitable expression in the appended claims, whatever features of patentable novelty exist in the invention disclosed.

In the accompanying drawing:

Figure 1 is a side elevation of a cement process shoe of openwork construction, embodying features of the invention;

Figure 2 is a bottom perspective of an insole provided with an attaching and filler strip according to the invention;

Figure 3 is a perspective of a fragment of insole showing an edge binding secured by the same stitches which hold the attaching and filler strip of the invention;

Figure 4 is a perspective of the forepart of the shoe of Figure 1, with a fragment of outsole broken away;

Figure 5 is an elevation in section 5—5 of Figure 1, on a larger scale; and

Figure 6 is an elevation in section on 6—6 of Figure 4.

Referring to the drawing, the shoe of Figure 1 is representative of cement process shoes in general, having an upper 10, insole 12 and outsole 14. As illustrated, the upper is of an openwork style wherein the edge of the insole would be visible at the voids in the upper. The invention is illustrated as it may be applied in cases where the insole is of inexpensive stock, such as paper, or the like. In such, because portions of edges of insole are to be exposed, the entire edge, or at least any portion which is to be exposed, is finished by being covered with a binding material of color and texture to combine well with the upper in the attainment of a generally pleasing aesthetic effect. But it should be understood that such an edge binding is not requisite to the attainment of the herein disclosed advantages, and that certain advantages of the invention apply to a McKay type of openwork shoe as well as to cement process shoes in general.

According to the invention a usual insole 12 may be made and cut to desired size and shape by methods and apparatus as now employed. My attaching and filler strip 16 is stitched to the insole as at 18 along the marginal edges of the insole, with a substantial thickness and width of body of the strip extending inward from the stitches, for serving as a filler between insole and outsole at regions where these elements, without it, would not become satisfactorily adhered together—because their surfaces which face together are in planes at a little distance from each other. Conveniently the strip 16 may be a length of cotton tubing which, preferably, will contain a filler of cotton or the like, such as the group of several yarns 20 (Figure 3). This tubing may be compressed to flatness, at its edge which is to be stitched to the insole, while the body of the strip bulges with respect to the stitched portion, and so can constitute a filler.

When the edges of insole 12 are to be bound, the binding 22 may be stitched to the insole simultaneously with strip 16, and by the same stitches. Heretofore the putting on of such a binding has frequently involved difficulties, because a work-feeding-means does not take hold of the binding effectively, due to the slippery nature of the type of binding material which often is used, resembling patent leather. But when the binding is applied simultaneously with the strip 16, with the strip 16 overlying the bind-

ing, both may be applied and stitched smoothly and efficiently with an ordinary walking foot sewing machine, whose walking foot readily takes hold of the compressible cotton so that it can coact with the feed dog for effective feeding of the work.

The strip 16 will be applied at the margin of the insole on that face which will come next to the outsole in a finished shoe, and it may extend all around the insole, or may be only at particular regions of insole, including the heel.

The lasting of a cement process shoe with an insole as above described, and as shown in Figures 2-5, proceeds according to present practices. If the upper is not of a cut-out style, the filler 16 advantages of the strip 16 will occur principally along the shank where the introduced stiffener 24 ordinarily prevents adhesive securement of outsole to insole except where there are portions of the upper. But the strip 16 of the invention extends as a filler in the space usually left vacant between insole and outsole, along each side of the shank stiffener; and this strip may be cemented to both insole and outsole at these regions, to improve the structure of the shank, and to increase the strength of attachment of insole to upper along this important region of a finished shoe. With such a full-bodied upper the binding 22 might be omitted.

With an openwork upper as portrayed, the advantages above described are present at the shank, and the strip 16 serves additionally as a filler and attaching means between discontinuous lasted-over portions of the upper. Referring to Figure 4, the strip portions 11, 11 of upper are shown lasted over upon the strip 16, compressing the strip where they engage it, but leaving the strip bulged as at 17, between the straps 11, 11. As the outsole 14 is laid in place, it can be effectively cemented to the lasted-over straps 11, 11 in the customary way, and, by the invention, the outsole also may be secured to the insole at the regions between straps 11, 11 because the strip 16 fills the space which otherwise would be vacant, and is stitched to whole thickness of insole and cemented to the outsole, and may additionally be cemented to the insole. Besides providing a stronger attachment of the outsole, the invention improves the appearance of the finished shoe by eliminating visible openings between insole and outsole, and by making no ridges in outsole and insole such as sometimes result from efforts to close these edge openings by severity of pressure.

The strip 16 can provide the said filler advantages in openwork McKay type shoes as well as in cement process shoes.

It is an important feature of the invention that my strip 16 is stitched through the insole and thus is securely anchored to the full thickness of insole. Because of this the pull of the outsole does not generate a tendency for the insole to become split, and to peel, as has happened heretofore when paper stock insoles have been used in cement process shoes.

If the insole is of a better quality not subject to danger of peeling or splitting, the securement of the strip 16 may be by cement alone. As the filling strip intervenes between outsole and insole and is ultimately to be secured to both the outsole and the insole, its initial application may be to either of these soles, and its joinder to the other of them will follow when the outsole is applied to the insole. The illustrated arrangement in which the strip lies between the upper

and the insole, is believed more convenient and is preferred, rather than the alternative equivalent in which it is between the upper and the outsole, stitched or cemented to the margin of the outsole, on that side of the outsole which is to face the insole.

I claim as my invention:

1. In a shoe having an openwork upper, an insole and an outsole, the combination wherein the insole has an edge-binding visible through openings in the upper, and a compressible filling strip is positioned along the margin of the insole and overlies said binding on one side of the insole; and a line of stitches secures together the binding, the filling strip and the insole; said strip having a body of breadth and thickness inward from said stitches sufficient for constituting a filler between the marginal portions of the insole and outsole at said openings.
2. An insole for shoes having a marginal compressible strip stitched to one face thereof, said strip having its full breadth inside of the edge of the insole and having sufficient thickness and breadth of body to fill space between and attach together the insole and outsole when an upper is inserted between the insole and outsole, said strip being of material which is readily permeable by cement at its surface which will come next to the outsole.
3. An insole for shoes having an edge-binding, a marginal compressible strip and stitches through the strip, the binding and the full thickness of insole; said strip having sufficient breadth and thickness of body inward from its stitches for constituting a filler between the marginal portions of the insole and an outsole when an outsole is combined with the insole.
4. An insole for shoes, as in claim 3, wherein the said compressible strip is a cotton fabric tube having filler threads of cotton extending longitudinally within the tube.
5. In a shoe having an upper, insole and outsole, the combination wherein a strip of compressible material which, at both surfaces there-

of, is readily permeable by cement is secured by stitching along the margin of one of said soles, with its full breadth inside of the edge of that sole, and intervenes between the insole and the outsole, constituting an attaching and filler element between lasted-over portions of the upper and the insole, and between the insole and the outsole at locations where there is no upper.

6. In a shoe having an upper, insole and outsole, the combination wherein the insole has its edge bound with a material which is not readily permeable by cement, and wherein a strip of compressible material which is readily permeable by cement is secured by stitching along the margin of the insole so as to overlie a turned over portion of said binding material, with the said stitching extending through the compressible material, binding material and insole; said compressible material intervening between the insole and the outsole, for constituting an attaching and filler element between the upper and the insole and between the insole and the outsole at locations where there is no upper.

7. In the manufacture of openwork shoes the method of making the juncture of insole and outsole, comprising the providing of an insole having a binding strip folded over its edge, and having a cement-permeable, compressible, filling strip laid over that portion of the binding strip which is at the marginal face of the insole that will be toward the outsole, the two said strips being secured to the insole by stitches which extend through the filling strip, binding strip and insole; the applying of cement to said filling strip; lasting the discontinuous portions of the upper over the insole, thus thinning the filler strip under them by compressing it, but leaving said strip elsewhere at approximately its original thickness; and then applying the outsole to the insole, with the lasted-over portions of upper, and said strip, intervening between insole and outsole.

ARAM DAGDIGIAN.
